AUXILIARY MAKE-UP CIRCUIT FOR GAS
TURBINE PLANTS

Walter Traupel, Winterthur, Switzerland, assignor to Sulzer Frères, Société Anonyme, Winterthur, Switzerland

Application January 30, 1945, Serial No. 575,294
In Switzerland March 18, 1944

8 Claims. (Cl. 60—49)

1

The invention relates to a gas turbine plant in which air from the atmosphere is continuously supplied to a circuit of working medium. The invention is characterised in that at least one compressor is coupled by means of a discon-nectible coupling to the turbine giving up the useful output, this compressor introducing the air into the circuit at a higher pressure when the output of the whole plant is greater, while at a smaller output the compressor is cut out by means of the coupling and the air is supplied to the circuit at a lower pressure. It is expedient for the air compressor to be driven by the useful output turbine by means of a fluid coupling that can be emptied.

An embodiment of the invention designed as a ship's propulsion plant is explained below in more detail with the aid of the drawing, which illustrates that embodiment diagrammatically.

The working medium compressed by the low-pressure compressor 1 passes through the intermediate cooler 2 into the high-pressure compressor 3 and is preheated in the tubes of a recuperator-heat exchanger 4. At the point 6 in the outlet pipe 5 of the recuperator the flow of working medium is divided up. A part passes through the pipe 7 into the heater 8 and is fur-ther heated while flowing over the heat-exchange tubes of the heater.

The working medium now compressed to the highest working pressure and heated to the highest working temperature passes through the pipe 9 into the turbine 10, is there expanded and then flows through the pipe 11 into the heat ex-changer 4. While flowing through the heat-ex-changer tubes it gives up part of its residual heat to the compressed working medium. A further part of its residual heat is given up to a cooling medium in the cooler 12, whereupon the working medium flows back to the low-pressure com-pressor 1 and the circuit here recommences.

A further part of the flow of working medium divided at the point 6 is extracted from the circuit and supplied through the pipe 13 to the burner 14 of the gas heater 8. The combustion gases flow through the heat-exchange tubes and then pass through the pipe 15 into the turbine 16, from which after expansion they are led off through the pipe 17 to be disposed of in any of the known ways of handling gas turbine exhaust. Through

the pipes 18 or 30 air is continuously supplied as make-up air for the part extracted at the point 6, to the open circuit of working medium taking place in the plant.

5 The turbine 10 operated by the flow of working medium in the circuit drives the compressors 1 and 3. Further, an electric auxiliary machine 22 is coupled to the compressors 1 and 3, and this can supply additional power to the compressors 10 when the plant is being started up and also in case of lack of power during service. If on the contrary an excess of power presents itself in the turbine 10, this can be led off through the electric machine 22, in the form of electric energy, to the mains. The turbine 16, operated by the quantity extracted, generates the useful output given up to the outside. This useful output tur-bine drives, for instance, the ship's propeller 21 through the reduction gear 19, 20.

15 The two compressors 23 and 24 are coupled to the turbine 16 generating the useful output through the reduction gear 19, 20 and the fluid couplings 25 and 26 respectively, which can be emptied. The compressor 23 draws air from the atmosphere through the pipe 27 and conducts it in a compressed state to the cooler 28. The cooled air is supplied through the pipe 29 to the compressor 24 and finally introduced through the pipe 30 into the circuit of the working medium

20 at the point 31 between the heat exchanger 4 and the cooler 12. At the point 32 a pipe 33 connects up, through which air can be supplied to the compressor 24 direct from the atmosphere when required. The two valve members 34 and 35 serve 25 for switching over the service. A further valve member 36 prevents any flow into the pipe 30 in case the two compressors 23 and 24 should not be in service.

30 If when the vessel is proceeding at cruising speed the plant is to produce a small output only, the member 36 in the pipe 30 is closed. The com-pressor 1 then draws in working medium as it becomes available through the cooler 12 and also 35 fresh air through the non-return member 37 from the pipe 18. Approximately atmospheric pres-sure will then prevail at the inlet of the com-pressor 1. The compressors 1 and 3 compress this working medium to a pressure of about 5 atmospheres, which will still prevail, apart from the

small pressure drop resulting from resistance to flow, at the entry to the turbines 16 and 10.

If the output is to be increased for purposes of greater vessel speed, the sequence of pressures in the circuit of the working medium is raised. First the fluid coupling 26 is filled and the compressor 24 is thereby brought into service. The member 34 must be closed and the members 35 and 36 open. The compressor 24 then draws in air from the atmosphere through the pipe 33 and conducts it at an increased pressure of about 4 atmospheres into the circuit at the point 31. The non-return member 37 is closed by the increased pressure, so that escape of the air through the pipe 18 is prevented. Working medium then flows to the compressor 1 at the delivery pressure of the compressor 24, apart from the slight pressure drop resulting from resistance to flow. The final pressure at the outlet from the compressor 3 and the inlet pressure into the turbines 16 and 10 are correspondingly raised to about 20 atmospheres, so that a higher power is available for driving the ship's propeller 21.

For travel at top speed the compressor 23 is also brought into service by filling the fluid coupling 25. The member 34 is opened and the member 35 closed, so that air is drawn in from the atmosphere through the pipe 27, cooled in a state of intermediate compression by the cooler 28 and further compressed by the compressor 24. The two compressors together then compress the air to about 8 atmospheres. This pressure, less the slight pressure drop resulting from resistance to flow, also prevails at the inlet to the compressor 1, and thus the delivery pressure of the compressor 3 rises to about 40 atmospheres. The whole sequence of pressures in the circuit is raised to 8 times the pressures prevailing in service at cruising speed. The output given up to the outside then rises to 15 times the output at slow speed.

The advantage of the plant described consists in that the turbines can be designed for the conditions at cruising speed, for which the best efficiency is maintained. The output of the plant can nevertheless be raised to a multiple of the output at cruising speed.

While I have described my invention in detail in terms of a specific structure, I do not wish to be limited to the details of the disclosed construction. It is apparent that many changes can be made therein within the spirit of my invention. For example, in a twin-screw installation with separate useful output turbines on each shaft, the low-pressure auxiliary make-up compressor could be driven by disconnectable coupling from one shaft and its high pressure counterpart from the other. Or other known forms of disconnectable coupling can be substituted for the preferred fluid type illustrated. Hence, for an understanding of the scope of the invention, reference is to be made to the appended claims.

I claim:

1. In a gas turbine plant, a working medium circuit including a compressor, a gas heater, a turbine and conduit means for conducting a gaseous working medium in the circuit through the compressor, the gas heater, the turbine and back to the compressor, a second turbine driven by working medium extracted from the circuit, one of said turbines driving said circuit compressor and the other of said turbines driving the plant useful load, disconnectable coupling means on the one of said turbines driving the useful load,

a second compressor driven from said coupling means, an intake from the atmosphere leading to said second compressor, and conduit means for delivering the output of said second compressor to a spot in the circuit before the first compressor.

2. The combination of claim 1 in which the disconnectable coupling means comprises a fluid coupling.

3. In a gas turbine plant, a working medium circuit including a compressor, a gas heater, a turbine and conduit means for conducting a gaseous working medium in the circuit through the compressor, the gas heater, the turbine and back to the compressor, a second turbine driven by working medium extracted from the circuit, one of said turbines driving said circuit compressor and the other of said turbines driving the plant useful load, disconnectable coupling means on the one of said turbines driving the useful load, a second and a third compressor driven from said coupling, an intake from the atmosphere leading to said second compressor, conduit means for delivering the output of said second compressor to the third compressor, conduit means for delivering the output of said third compressor to a spot in the circuit before the first compressor, and an intake from the atmosphere leading to said third compressor.

4. The combination of claim 3 in which the conduit means connecting the second and third compressors contains a cooler.

5. In a gas turbine plant, a working medium circuit including a compressor, a gas heater, a turbine driving said compressor, a recuperator, a cooler and conduit means for conducting a gaseous working medium in the circuit through the compressor, the gas heater, the turbine, the recuperator and the cooler and back to the compressor, a conduit for extracting part of the working medium from the circuit and delivering it to the burner of the gas heater, a second turbine driven by the combustion gases of the gas heater and driving the plant useful load, compressor means disconnectably driven by said second turbine, an intake from the atmosphere leading to said compressor means, and conduit means for delivering the output of said compressor means to the circuit.

6. The combination of claim 5 in which the output of the compressor means is delivered to the circuit between the recuperator and the compressor.

7. The combination of claim 6 in which an intake from the atmosphere is provided in the circuit between the cooler and the compressor.

8. In a gas turbine plant, a working medium circuit including a compressor, a gas heater, a turbine driving said compressor, a recuperator, a cooler and conduit means for conducting a gaseous working medium in the circuit through the compressor, the gas heater, the turbine, the recuperator, the cooler and back to the compressor, intake means from the atmosphere leading to said compressor, a conduit for extracting part of the working medium from the circuit and delivering it to the burner of the gas heater, a second turbine driven by the combustion gases of the gas heater and driving the plant useful load, compressor means disconnectably driven by said second turbine, said compressor means comprising a second and third compressor, an intake from the atmosphere leading to said second compressor, conduit means for delivering the output of said second compressor to said third com-

pressor, conduit means for delivering the output of said third compressor to the circuit between the recuperator and the first compressor, an intake from the atmosphere to the conduit connecting said second and third compressors and valve means in the intake to the first compressor, in the intake to the second compressor, intermediate said second and third compressors and intermediate said third compressor and the circuit whereby air from the atmosphere can be admitted to the circuit through the first, the first and second, or the first, second and third compressors at will.
